Application filed March 7, 1889. Serial No. 302,340. Term of patent 3½ years.

To all whom it may concern:

Be it known that I, JAMES L. FOLSOM, a citizen of the United States, residing in Brooklyn, county of Kings, and State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design is composed of flower and leaf forms mainly conventionalized. The prominent figures are composed of groups of such ornamentation. A curved stem-work joins most of the prominent figures, and smaller 20 groups of leaf and flower forms are interspersed between the larger figures.

What I claim as new, and desire to secure by Letters Patent, is—

The design for carpets, consisting of the de- 25 sign substantially as shown.
